STOP FOR PICKER MECHANISMS

Elliot A. Santon, Worcester, Mass., assignor to
Crompton & Knowles Loom Works, Worcester,
Mass., a corporation of Massachusetts

Application June 23, 1942, Serial No. 448,083

11 Claims. (Cl. 139—147)

This invention relates to improvements in stops for loom picker mechanism and it is the general object of the invention to provide convenient and efficient means for arresting movement of the heavy moving parts of the picker mechanism in time to prevent breakage of the picker stick when the latter strikes its bunter.

It is customary in certain types of looms to employ a picker shaft on which is mounted a picker cam and a picker arm connected by a sweep stick and lug strap to the picker stick. A rotation arm on the bottom shaft of the loom engages the cam to rock the picker shaft in a direction to move the picker arm, sweep stick and lug strap, inwardly to actuate the stick at the time of picking. The picker shaft is ordinarily free to rotate in its bearings and acquires a momentum which ordinarily is stopped by engagement of the picker stick with its bunter. The rotational force of the picking shaft is communicated to the stick through the sweep stick and it is for this reason that the stick is required to withstand the checking force which stops rotation of the picker shaft. It is an important object of my present invention to provide a stop to engage a part moving with the picker shaft so that the latter and the parts moving with it may be stopped prior to engagement of the picker stick with its bunter at the end of the picking stroke. By the use of my invention the only force which acts to break the picker stick at the end of the picking stroke is that required to stop the motion of the stick itself.

It is a more specific object of my present invention to provide a picker mechanism stop including an upright on which is vertically slidable a sleeve resting on a cushion of some soft elastic material such as rubber and in the upper part of which is located a leather pad to receive the blow of a stop arm on the picker shaft.

With these and other objects in view which will appear as the description proceeds, my invention resides in the combination and arrangement of parts hereinafter described and set forth.

In the accompanying drawing, wherein a convenient embodiment of my invention is set forth,

Fig. 1 is a front elevation of a part of one end of a loom showing my invention,

Fig. 2 is a side elevation of a picker shaft and associated parts looking in the direction of arrow 2, Fig. 1,

Fig. 3 is a vertical section on an enlarged scale of structure on line 3—3 of Fig. 2,

Fig. 4 is a vertical section through the sliding

sleeve prior to application thereto of the shock absorbing pad.

Fig. 5 is a vertical section through the stationary upright forming a part of my invention and showing the resilient washer made of rubber or the like, and

Fig. 6 is a vertical section on line 6—6, Fig. 1.

Referring particularly to Figs. 1 and 2, I have shown a loom frame 10, lay 11 and shuttle S 10 which is propelled by a picker 12. A picker stick 13 for the picker 12 is pivoted at 14 to a rocker foot 15 mounted on a rocker shaft 16 journaled for oscillation in the lower part of the loom frame. A picker shaft 17, which may be rectangular in cross section, is rockably mounted in front and back bearings 18 and 19, respectively, secured to the loom frame. Mounted on the shaft 17 is a picker shoe 20 having a cam 21 for engagement with a roll 22 on a picker arm 23 secured to the bottom shaft 24 of the loom. The picker shoe is held in position on the shaft 17 by set screws 25.

The picker arm 30 has a hub 31 secured to the shaft 17 by a set screw 32. The upper part of the picker arm is pivoted as at 35 to a sweep stick 36 the outer end of which is connected as at 37 to a lug strap 38. The lug strap is of the usual U-shaped form and extends around the picker stick 13 and is held in vertical position on the latter by a holder 39. There is a certain amount of lost motion between the lug strap and picker stick as indicated in Fig. 6. The outer or right hand part of the lug strap bears tightly against the right edge of the picker stick as seen in Fig. 1 during picking operation, but the picker stick is free to move a limited amount to the left relatively to the lug strap at the end of the picking stroke, as suggested by space 42 in Fig. 6.

In the operation of the mechanism thus far described rotation of the bottom shaft 24 causes periodic engagement between the roll 22 and the cam 21 to rock the picker shaft 17 in a counter-clockwise direction as viewed in Fig. 1 as the lay 11 recedes to cause inward movement of the picker stick 13 to the left, Fig. 1, to propel the shuttle S to the opposite side of the loom. A usual incident in the operation of the picking mechanism is that the shaft 17 and the parts mounted on it continue their motion after the cam and roll separate due to their momentum. This excess movement ordinarily transmits a force through the arm 30, sweep stick 36 and lug strap 38 to the picker stick to cause the latter to move

against its lay carried bunter 45 with sufficient force to strain or break the stick.

My present invention provides means for arresting the overthrow of the picker mechanism before the picker stick strikes its bunter 45. In carrying my invention into effect I provide a stand 50 having an upright stem 51 preferably cylindrical and mounted on a foot 52 through which extend bolts 53 by which the stand is secured to the floor on which the loom rests. A cap 55 is provided with an internal bore 56 which fits snugly around the stem 51 but is free to slide vertically thereon. A vertical slot 57 in the lower part of the cap receives a stop screw 58 tapped into a threaded hole 59 in the stem 51 as shown in Fig. 3, to limit vertical movement of the cap on the stem.

The cap 55 has a horizontal head 60 which rests on a resilient body or disk 61 made of soft rubber or some similar material resting on the top of stem 51. The upper surface of head 60 is provided with a recess 65 undercut as at 66 to receive a leather washer 67. The latter is preferably of the same diameter as the small or upper diameter of the recess 65 and the washer is preferably somewhat thicker than the depth of the recess to project above the cap. The leather washer is driven into the recess and its lower part eventually spreads into the bottom of the recess. A hub 70 is secured to the shaft 17 and has a stop arm 71 which may be formed as shown in Fig. 1 to extend over the washer 67.

In assembling, the stand 50 is secured in position by the bolts 53, the rubber body or disk 61 is placed on top of stem 51, the cap 55 is then fitted down over the disk 61 and upper end of the stem and the stop screw 58 passed through the slot 57 and threaded into the tapped hole 59. The screw 58 prevents accidental removal of the cap 55 from the stem and permits downward motion of the cap to compress the rubber disk.

In operation, the parts will be so set that the arm 71 will strike the leather washer 67 shortly after the roll 22 passes beyond the left extremity of the cam 21 as viewed in Fig. 2 and before the picker stick strikes its bunter 45. The momentum of rotation of the shaft 17 and the parts connected to it will be arrested partly by the inertia of the cap 55 and partly by the resilience of the rubber disk 61, but the picker stick is free to continue its movement in slot 42 of the lug strap until it strikes the bunter 45. It is for this reason that the only force which drives the picker stick against the bunter is its own momentum. The force of stopping all the parts of the picking mechanism up to and including the lug strap is exerted against my improved stop and is not communicated to the picker stick.

In the operation of my invention it is found that breakage of picker sticks is greatly reduced without impairing the efficiency of the picking mechanism. While I have stated that the arm 71 does not engage the leather pad 67 until after the roll 22 has left the cam 21, yet I do not wish to be limited to this relationship, inasmuch as the resilience of the disk 61 will permit engagement of the arm 71 with the leather pad while the roll 22 is still in engagement with the left part of the cam 21. It is also to be understood that although rubber and leather have been specified as the materials of which parts 61 and 67, respectively, are made, I do not wish thus to be limited and these parts if desired can be made

of materials having the same general characteristics as rubber and leather.

From the foregoing it will be seen that I have provided a simple form of stop for a loom picking mechanism including a fixed stand and a cap slideable thereon against the action of a shock absorbing disk or the like made of rubber or some similar material. The arm 71 moves with all of the parts attached to the picker shaft and therefore serves to stop the latter prior to engagement of the picker stick with its bunter.

Having thus described my invention it will be seen that changes and modifications may be made therein by those skilled in the art without departing from the spirit and scope of the invention and I do not wish to be limited to the details herein disclosed, but what I claim is:

1. A picker mechanism stop for a loom having a picker shaft provided with a stop arm, said stop including a stationary base member, a second member normally out of contact with said stop arm to be engaged and moved by the stop arm relatively to the first member when the shaft rocks on a picking movement thereof, one of said members being hollow to receive the other member and one of said members supporting the other member, and a body of soft elastic material located within the hollow member for engagement with the other member to hold said members in normal relative position with the second member in position for engagement with said stop arm, said body being yieldable to permit relative movement of said members by the stop arm.

2. A picker mechanism stop for a loom having a picker shaft provided with a stop arm, said stop including a stationary base member, a second member to be moved by the stop arm relatively to the first member, one of said members being hollow to receive the other member, a body of soft elastic material located within the hollow member for engagement with the other member to hold said members in normal relative position with the second member in position for cooperation with the stop arm, said body being yieldable to permit relative movement of said members by the stop arm, and a shock absorber carried by the second member for engagement with the stop arm.

3. A picker mechanism stop for a loom having a picker shaft provided with a stop arm, said stop including a stationary base member, a second member to be moved by the stop arm relatively to the first member and having an undercut opening in the part thereof adjacent to said stop arm, one of said members being hollow to receive the other member, a body of soft elastic material located within the hollow member for engagement with the other member to hold said members in normal relative position for cooperation with said stop arm, said body being yieldable to permit relative movement of said members by the stop arm, and a shock absorber held in said undercut opening and positioned for engagement with the stop arm.

4. A picker mechanism stop for a loom having a picker shaft provided with a stop arm, said stop including a stationary base member, a second member to be moved by the stop arm relatively to the first member, one of said members being hollow to receive the other member, a body of soft elastic material located within the hollow member for engagement with the other member to hold said members in normal relative position for cooperation with the stop arm, said body being yieldable to permit relative movement

of said members by the stop arm, and means on one of said members to engage the other member and limit relative movement of said members.

5. A picker mechanism stop for a picker shaft having a stopping arm thereon, said stop including a stationary base, a cap vertically slideable on and surrounding the upper part of the base; and a body of shock absorbing material within the cap and supported by the base and on which the cap normally rests, said body of shock absorbing material holding the cap in position for engagement by said arm and yielding resiliently to permit movement of the cap by said arm with respect to the base.

6. A picker mechanism stop for a loom having a picker shaft having a stop arm secured to and moving with the shaft, said stop including a stationary base having an upright stem, a hollow member slideable vertically on said stem and having a horizontal head extending over said stem, a soft rubber disk within the member and located between said head and the stem, and means to limit upward movement of the member with respect to the stem, said member being movable along said stem by said arm against the action of said rubber disk to stop the shaft.

7. A picker mechanism stop for a loom having a picker shaft provided with a stop arm, said stop including a stationary base having an upright stem, a hollow member slideable vertically on said stem and having a horizontal head extending over said stem, a body of soft elastic rubber within said member between said head and the stem, and a shock absorber secured to the upper surface of said head for engagement with said arm, the latter when engaging the shock absorber moving the member against the action of said body.

8. In a loom having a picker stick to be given a picking stroke by a picker shaft provided with a stop arm, a fixed upright member, an impact member for engagement with the stop arm, one of said members being hollow to receive the other member and said members being relatively slideable, and a body of resilient shock absorbing material within the hollow member positioned for engagement with the other member, said body normally holding the impact member in posi-

tion for engagement with the stop arm prior to completion of the picking stroke of the picker stick, and said body being compressible to assist in stopping movement of said stop arm and picker shaft.

9. In a loom having a picker stick to be given a picking stroke by a picker shaft provided with a stop arm, a fixed upright, a cap surrounding the upper end of the upright and slideable thereon, and a body of soft resilient material within the cap held by the latter in position for engagement with said upright, said body normally holding the cap in position for engagement with the stop arm prior to completion of said picking stroke, said body being compressible to assist the stopping movement of the shaft by engagement with the stop arm by the cap.

10. In a loom having a picker shaft to give a picker stick connected thereto a picking stroke, said shaft having a stop arm secured thereto, a fixed member, a second member movable along and guided by the first member, one of said members being hollow to receive the other member, a body of elastic shock absorbing material within the hollow member and held thereby in position for engagement with the other member, said body of elastic material holding said other member in position for engagement by said stop arm to exert a stopping force on the shaft prior to completion of the picking stroke of the picker stick.

11. In a loom having a picker shaft to give a picker stick connected thereto a picking stroke, said shaft having a stop arm secured thereto, a fixed member, a second member movable along and guided by the first member, a yieldable pad on the second member to communicate a force to the latter from the stop arm, one of said members being hollow to receive the other member, a body of elastic shock absorbing material within the hollow member and held thereby in position for engagement with the other member, said body of elastic material holding said other member with said pad in position for engagement by said stop arm to exert a stopping force on the shaft prior to completion of the picking stroke of the picker stick.

ELLIOT A. SANTON.
